FREQUENCY CONTROLLED ELECTRONIC OSCILLATOR

Irving Wolff, Merchantville, N. J., assignor to Radio Corporation of America, a corporation of Delaware

Application July 25, 1936, Serial No. 92,614

6 Claims. (Cl. 179—171)

In its broad aspects, this invention relates to electronic oscillators. More specifically, the invention is a carrier frequency control for a modulated electronic oscillator.

An electronic oscillator or magnetron may be used to generate ultra high frequency oscillatory currents; i. e., currents of a frequency of thirty megacycles and upwards. If a magnetron oscillating at three thousand megacycles, by way of example, is modulated, the modulation currents will not only modulate the amplitude of the oscillations but will greatly vary the frequency of the carrier current. This invention contemplates stabilizing the frequency of the carrier current of a modulated magnetron oscillator.

One of the objects of my invention is to provide means for stabilizing the frequency of an electronic oscillator. Another object is to provide an oscillator for controlling the frequency of the carrier currents of a modulated magnetron oscillator.

A further object is to provide means for preventing a controlling oscillator from being affected by the oscillator to be controlled.

In the accompanying drawing, Fig. 1 represents a schematic illustration of my invention, and

Fig. 2 is a circuit diagram of a modulated magnetron oscillator whose carrier frequency is controlled.

Referring to Fig. 1, a magnetron oscillator 1 is adjusted to establish a carrier frequency of 3000 megacycles, by way of example. Signalling or modulating currents are impressed on the oscillator 1 by a modulator 3. The effect of the modulation currents is to vary both the amplitude and frequency of the carrier current. The frequency may be stabilized or controlled by impressing currents of carrier frequency, which are unmodulated, on the modulated oscillator. If the control currents of carrier frequency are impressed directly from the control oscillator 5 on the unmodulated oscillator 1, the resulting frequency will be determined by the relative reaction of the two oscillators. That is, the control oscillator 5 may control the oscillator 1 or be controlled by that oscillator.

The interaction may be prevented by generating currents of a frequency of 1500 megacycles. The currents of 1500 megacycles frequency are transferred to the oscillator 1 through a frequency doubler 7. The frequency doubler, as the title implies, increases the control frequency currents from 1500 megacycles to 3000

megacycles. The frequency doubler not only increases the frequency but it also prevents controlled and controlling oscillators from interacting. Thus the oscillator 1 is frequency controlled or stabilized by the control oscillator 5. Modulation currents may now be impressed on the oscillator 1 and will vary the amplitude of oscillation without varying the frequency of the carrier currents.

One embodiment of my invention is illustrated in Fig. 2. The magnetron oscillator 9 is composed of an evacuated envelope 11. A pair of anodes 13 and a cathode 15 are suitably mounted within the envelope 11. A magnetic field, whose lines of force are substantially parallel to 15 and surround the cathode, is established by a solenoid 17, permanent magnet, or the like. The solenoid 17 may be energized by a battery 19. The cathode 15 is heated by a battery 21. The anodes 13 are connected to a resonant transmission line 23 which terminates in a dipole antenna 25. The anode circuit is comprised of an anode battery 27, which is serially connected, through the secondary 29 of a modulation transformer 31 and radio frequency choke coil 33, to a point intermediate the ends of the dipole 25. The modulation is effected by a microphone 35 which is connected through a battery 37 to the primary 39 of the modulation transformer 31.

The circuit thus far described is a conventional modulated magnetron oscillator 9. The control oscillator 41, which operates at half the carrier frequency of the modulated oscillator 9, is comprised of an evacuated envelope 43 which includes a cathode 45 and a pair of anodes 47. The envelope is surrounded by a solenoid 49 which is energized by a battery 51. The cathode 45 is energized by a battery 53. The anodes 47 are connected to a resonant transmission line 55. An anode battery 57 is connected from the cathode 45 through a radio frequency choke coil 59 to the mid-point of the transmission line 55.

The transmission line 55 is suitably coupled to another transmission line 61. The latter transmission line is terminated in a full wave rectifier 63, whose output currents are of double the frequency of the input currents. The output of the rectifier is impressed on a pair of 50 enclosed quarter wave lines 65, 67 between terminals which offer a suitable impedance match for the full wave rectifier, or frequency doubler.

The quarter wave lines 65, 67 are respectively connected to the transmission line 23 by leads 55

- 69, 71 which include "trombones" 73, 75 or the like, for tuning the connecting lines 69—71. The several transmission lines may be terminated in sections of line which offer suitable impedances.
- 5 Inasmuch as constant frequency is desired, the oscillators and transmission lines should be carefully designed and constructed to minimize changes caused by the ambient temperature, vibration, voltage variations, and the like.
- 10 Thus I have described a modulated magnetron oscillator. The carrier frequency currents generated by this oscillator are controlled. The controlling oscillator creates unmodulated oscillatory currents which have half the frequency of the 15 modulated carrier currents. The frequency of the controlling oscillator currents is doubled by full wave rectifiers or the like. The controlling currents of the frequency of the carrier are impressed through suitable transmission lines on 20 the modulated magnetron oscillator to stabilize or control the frequency of the carrier currents and thereby prevent frequency modulation.
- 25 Although I have chosen magnetron oscillators to illustrate my invention, it should be understood that Barkhausen-Kurz or any type of ultra high frequency oscillator may be used. Likewise the controlling frequency may be made less than half of the carrier and multiplied by more than two to control the carrier frequency.
- 30 I claim:
1. An ultra high frequency system comprising an ultra high frequency oscillator for generating carrier frequency currents, means for impressing modulating currents on said oscillator, a second 35 oscillator for generating currents of less than said carrier frequency, means for multiplying the frequency of said controlling current to equal the carrier frequency, a pair of resonant lines for stabilizing the frequency of said multiplied frequency currents, means for impressing said multiplied frequency currents on said pair of resonant lines, and means for impressing said multiplied and stabilized frequency currents on said ultra high frequency oscillator to thereby control 40 said carrier frequency currents.
  2. An ultra high frequency system comprising an ultra high frequency oscillator for generating carrier frequency currents, means for impressing modulating currents on said oscillator, a second 45 oscillator for generating currents of half said carrier frequency, means for doubling the frequency of said controlling currents, a pair of quarter wave resonant lines for stabilizing the frequency of said doubled frequency currents, means for impressing said doubled frequency currents on said pair of resonant lines, and means for impressing said doubled and stabilized frequency currents on said ultra high frequency oscillator to thereby control said carrier frequency currents.
  3. An ultra high frequency system comprising
- a magnetron oscillator for generating carrier frequency currents, means for impressing modulating currents on said oscillator, a second oscillator for generating currents of less than said carrier frequency, means for multiplying the frequency 5 of said controlling currents to equal the carrier frequency, a pair of quarter wave resonant concentric lines for stabilizing said multiplied frequency currents, means for impressing said multiplied frequency currents on said pair of concentric lines, and means for impressing said stabilized multiplied frequency currents on said magnetron oscillator to thereby control said carrier frequency currents.
4. An ultra high frequency signalling system 10 comprising, in combination, a magnetron oscillator for generating carrier frequency currents, means for modulating said carrier frequency currents with signal impulses, a second oscillator for generating controlling currents of half said 15 carrier frequency, means for impressing currents from said second oscillator on a full wave rectifier, a pair of enclosed quarter wave length lines resonant to the output currents from said rectifier for stabilizing the frequency of said rectifier 20 currents, means for impressing said rectified currents on said quarter wave length lines, and means for impressing the output currents thus stabilized on a transmission line coupled to said magnetron oscillator for controlling the frequency 25 of said carrier currents.
5. The method of controlling the frequency of modulated ultra high frequency carrier currents by means of a concentric resonant line which comprises generating an ultra high frequency carrier current, modulating said carrier current, and generating an unmodulated controlling current of a frequency equal to said carrier, stabilizing the frequency of said unmodulated controlling current by applying said current to said concentric resonant line, and applying said frequency stabilized controlling current to said modulated ultra high frequency carrier to control the frequency of said carrier currents.
6. The method of controlling the frequency of modulated ultra high frequency carrier currents by means of a resonant line which comprises generating an ultra high frequency carrier current, modulating said carrier current, generating 45 an unmodulated controlling current of lower frequency than said carrier frequency, multiplying said lower frequency current until its frequency equals said carrier frequency, stabilizing the frequency of the currents of said multiplied frequency by applying said multiplied frequency currents to said resonant line and impressing said multiplied and stabilized frequency current on said modulated ultra high frequency carrier to control the frequency of said carrier currents.
